DESIGN FOR A TACKING STITCHER

Anne M. O'Brien, Port Richmond, Staten
Island, N. Y.

Application November 22, 1940, Serial No. 96,744

Term of patent 14 years

To all whom it may concern:

Be it known that I, Anne M. O'Brien, a citizen of the United States and a resident of Port Richmond, county of Richmond, State of New York, have invented a new, original, and ornamental Design for a Tacking Stitcher, of which the following is a specification, reference being had to the accompanying drawing, forming part thereof, and in which:

I claim:

The ornamental design for a tacking stitcher, as shown,

ANNE M. O'BRIEN.
